UNITED STATES PATENT OFFICE.

MOÏS H. AVRAM, OF NEW YORK, N. Y., ASSIGNOR TO STANDARD SILICA BRICK MACHINERY COMPANY, OF WILMINGTON, DELAWARE.

KILN.

1,189,904.

Specification of Letters Patent.

Patented July 4, 1916.

Application filed September 16, 1913. Serial No. 790,010.

To all whom it may concern:

Be it known that I, Moïs H. Avram, a citizen of the United States, and a resident of New York city, county and State of New York, have invented certain new and useful Improvements in Kilns, of which the following is a specification.

This invention relates to a kiln of novel construction which may be used for drying various materials, although it is more particularly designed for hardening or steam indurating sand lime bricks and similar articles. My improved kiln is preferably made of reinforced concrete and constitutes a tubular chamber of considerable length the ends of which may be closed by suitable gates. The construction is such that the entrance gate and the exit gate are simultaneously operated from one end of the kiln, so that all unnecessary delay in operating the gates for charging and emptying the kiln is avoided.

In the accompanying drawing: Figure 1 is a side view of my improved kiln; Fig. 2 an enlarged vertical section on line 2—2, Fig. 1; Fig. 3 a vertical longitudinal section through one end of the kiln; Fig. 4 an end view, partly broken away, of the kiln, and Fig. 5 a modification of the concrete reinforcement.

My improved kiln consists of a tubular body or shell preferably made of concrete and comprising essentially a substantially flat bottom 10 and an integral curved roof 35 or top 11, said bottom and roof jointly forming a drying chamber 12. Within the top 11 of the kiln are embedded a number of spaced parallel longitudinal rods 13 which are connected by interlaced transverse wires 14 as illustrated in Figs. 2 and 3. To the lower ends of wires 14 are firmly attached the upper ends of, substantially, U-shaped wires or bails 15 that extend across and are embedded within the upper section of bottom 10. In lieu of wires 14, wire netting 14^a may be used for holding rods 13 in position (Fig. 5). The lower section of bottom 10 is reinforced by a suitable wire netting 16 extending throughout the entire bottom. Within the latter are embedded a pair of longitudinal rails 17 in such a manner that their heads project slightly beyond the upper surface of the bottom 10. In this way, a track is formed that extends through the en-

tire length of the kiln and is adapted for the support of a suitable number of trucks or cars 18, each car being provided with a flat top board 19, the width of which is slightly less than that of chamber 12. Upon each board 19 are stacked the bricks 20 to be hardened, in such a manner that the width of the pile thus formed diminishes from the bottom toward the top, care being taken that the contour of said pile resembles closely to the shape of the inner kiln-wall (Fig. 2). The size of the brick-piles should be such that just sufficient clearance is provided between them and the kiln-wall so as to permit an unobstructed travel of the cars.

Both ends of the kiln are adapted to be closed by gates which are preferably of the general construction described in Patent No. 888,573 granted to me for a kiln, on May 26, 1908. At each mouth of the kiln, there is embedded within the concrete sections 10 and 11, the flange 21 of a yoke 22, the shape of said flange being such that its inner surface extends flush with the inner surface of the kiln (Fig. 3). Opposite the opening of the latter, yoke 22 is provided with a circular opening which is adapted to be closed by a correspondingly shaped door or gate 23. Yoke 22 is further provided with an integral flange 24 and a removable flange 25, which form an intermediate guide way for a cross head 26. The latter is made integral with a disk or frame 27 provided with suitable strengthening ribs as illustrated in Fig. 4. Frame 27 has a central tubular hub 28 within which is guided a central stud 29 of gate 23. To stud 29 is secured a headed pin 30 which is influenced by a spring 31 tending to draw gate 23 outward. Into frame 27 are tapped a suitable number of clamp screws 32, the inner ends of which are adapted to bear against gate 23 thereby forcing the same against yoke 22. To screws 32 are secured overlapping toothed sectors 33 which engage a common toothed wheel 34 loosely mounted upon hub 28. To wheel 34 is rigidly connected a gear wheel 35 engaging a pinion 36 which is secured to one end of a pintle 37. The latter is loosely mounted within a toothed wheel 38 and carries at its other end a pinion 39 meshing with a stationary toothed wheel 40 keyed to hub 28. Pinions 36, 39 have an unequal number of teeth, one

of said pinions having preferably one more tooth than the other pinion. The result is that when wheel 38 is rotated, gear wheel 35 will be advanced for one tooth during each 5 complete rotation of wheel 38. Wheel 34 will thus make a corresponding partial revolution which by sectors 33, effects a rotation of screws 32. It will thus be seen that by properly operating wheel 38, all of the 10 screws 32 may be simultaneously advanced toward gate 23 or withdrawn therefrom. In this way, the gate is either forced against its seat, or spring 31 is permitted to withdraw the gate from said seat, so that it may 15 be readily raised as hereinafter more fully described. For simultaneously actuating the wheels 38 of both gates, a shaft 41 is provided which extends along the kiln and is supported in suitable bearings 42. Shaft 20 41 carries a pair of relatively fixed gear wheels 43 that engage wheels 38, while a hand wheel 44, secured to one end of shaft 41, may be used for rotating the same. For simultaneously raising both end frames 27 25 together with their gates 23, a suitably supported longitudinal shaft 45 is provided which carries a pair of worms 46 and a chain wheel 47, the latter being provided with a depending endless chain 48. Each 30 worm 46 engages a worm wheel 49 provided with a tapped central perforation which is engaged by a screw stem 50. The upper end of stem 50 is guided within a suitable bearing 51 of a cross piece 52 connecting 35 the vertical upper sections of yoke 23. The lower end of each stem 50 is, by a wedge 53, connected to frame 27. If it is desired to 40 open the gates of the kiln for removing the hardened bricks, and introducing unhardened bricks, hand wheel 44 is first operated to withdraw screws 32 from gates 23 in the manner above described. Chain 47 45 which is arranged in proximity to wheel 44 is then operated to cause a corresponding rotation of shaft 45 which, in turn, through worms 46 and worm wheels 47, will actuate screw stems 50 to raise frames 27 and gates 23. For closing the gates, the operation is 50 reversed as will be readily understood. At its bottom, chamber 12 is preferably provided with a longitudinal gutter 54 having a slight dip toward a drain pipe 55, so that any moisture, etc., condensed within chamber 12 may be readily withdrawn therefrom. Pipe 55 is controlled at a readily 55 accessible point by a suitable valve (not shown). The necessary steam for indurating the bricks may be admitted through a

suitable supply pipe 56 apertured as at 57 for the discharge of the steam. 60

It will be seen that my improved kiln has important advantages over the kilns hitherto used, and more particularly over the kilns used for steam indurating sand lime bricks. As these kilns are of considerable 65 lengths and where hitherto made of riveted iron tubes, the shipment thereof required special railroad cars which incurred delay and expensive shipment. With my improved construction, the kiln may be quickly 70 built at the plant where the bricks are made, the only articles that necessitate shipment being the gates of the kiln and connected parts. Furthermore, the kiln does not require any additional lining to prevent radiation of heat, nor does it require a special 75 foundation. One of the principal advantages, however, is that the peculiar shape of the kiln permits its capacity to be most economically utilized. The iron kilns hitherto used, had to be made in a cylindrical 80 shape owing to the high steam pressure to which they are subjected. As the platform of the truck carrying the bricks was necessarily arranged near the widest section of 85 said cylinder, its capacity was but imperfectly utilized, while with my improved concrete kiln, the capacity thereof is turned to the most useful account, as will be readily understood from Fig. 2 of the drawings. 90

I claim:

1. A kiln for steam indurating sand lime bricks, comprising a tubular shell made of reinforced concrete, said shell having a flat bottom and an integral curved top, a flanged 95 yoke partly embedded within said concrete at each end of the shell, a gate slidably engaging each yoke, rails embedded within the shell-bottom and adapted to support a brick-carrying truck, and means for admitting 100 steam into the interior of the shell.

2. A kiln for steam indurating sand lime bricks, comprising a tubular shell made of reinforced concrete, said shell having a curved top and an integral flat bottom provided with a longitudinal gutter, a flanged yoke partly embedded within said concrete at each end of the shell, a gate slidably engaging each yoke, rails embedded within the shell-bottom and adapted to support a 105 brick-carrying truck, and a perforated steam inlet pipe extending along the gutter. 110
